UNITED STATES PATENT OFFICE.

CHARLES H. ANDERSON, OF CINCINNATI, OHIO.

UNDERFRAME FOR CARS.

1,244,826.

Specification of Letters Patent. Patented Oct. 30, 1917.

Application filed September 13, 1916. Serial No. 119,913.

To all whom it may concern:

Be it known that I, CHARLES H. ANDERSON, a citizen of the United States, and a resident of Cincinnati, in the county of Hamilton and State of Ohio, have invented certain new and useful Improvements in Underframes for Cars; and I do hereby declare the following to be a full, clear, and exact description of the invention, such as will 10 enable others skilled in the art to which it appertains to make and use the same.

My invention relates to an improvement in car construction and particularly to parts of the underframe of electric or trolley cars, 15 the object being to provide improved means for the attachment of the hangers which carry pipes, air tanks, and electrical apparatus now in universal use on the modern electric car, and it consists in the parts and 20 combination of parts as will be more fully described and pointed out in the claims.

In the accompanying drawings, Figure 1 is a view in transverse section through a part of a car floor showing my improvement. 25 Fig. 2 is a view in transverse section through the cross-sill showing the manner of securing a pipe thereto. Fig. 3 is a view in elevation of a part of the sill and showing the pipe hanger and pipe. Fig. 4 is a view similar to Fig. 2, showing the manner of securing the floor to the sill, and Fig. 5 is a view in longitudinal section through a part of the car floor showing a hanger or carrier secured to two sills.

35 All electric cars carry considerable equipment, such as pipes, tanks and electrical apparatus, and with the cars as now constructed, it is necessary to first locate the various pipes and parts to be mounted on 40 the underframe and then drill holes at the proper points in the steel work for the attachment of the supporting hangers or bolts.

I attach all the parts to the cross-sills 1 of the underframe, each cross-sill being of 45 box form with an open slot 2 extending throughout its length, or at least through such parts thereof as are available for the attachment of supporting hangers. The metal at the side edges of the slot is turned back or doubled over as at 3, as clearly 50 shown in Fig. 2, so as to increase the area of the metal and make it balance the top chord, and each is preferably provided at

its sides with holes 4, which lighten up the 55 sills and also provide for access to the interior thereof for the manipulation of the bolts which secure the hangers in place.

In the drawings I have shown hangers for carrying pipes 5, which may be air, 60 steam, or water pipes, or conduits for electric wires; hangers for carrying a tank 6 and in Fig. 5 a hanger carried by two cross-sills. In each instance the securing bolts 7 are passed into the cross-sills through the 65 openings 4 and through the flat washers 7^a, 70 the side ends or edges of the latter, as the case may be, being turned down as at 8, so as to interlock with the turned up edges 3 of the sills. The washers bridge the slot in the sill and a single washer 7^a may 75 form the seat for one or more bolts securing a hanger 9, and as the washer is interlocked with the sill, it prevents any lateral spreading of the latter and also adds to its 75 strength.

In Fig. 5 I have shown a hanger 6^a supported at its ends by bolts carried by two adjacent cross-sills, with a carrying frame 10 bolted to the hanger 6^a. By slotting the hanger 6^a, or providing it with a series of 80 holes for the bolts 11, the mounting is practically universal, that is to say, the hanger 6^a can be located at any point throughout the length of the cross-sills and the carrying frame 10 at any point throughout the length 85 of the hanger 6^a.

If the floor boards or plates 12, be secured to the cross-sills 1 by screw bolts, as shown in Fig. 4, the nuts for securing the bolts, will be applied through the openings 90 or through the slots 4 in the sills.

With this improvement, the necessity for exact location will be eliminated, and the cost of drawings and the preliminary work of locating the parts saved. It gives universal facilities for locating and securing the several parts of the apparatus to the underframe and eliminates specially located holes, thus permitting the cross-sills to be standardized.

100 It is evident that various slight changes might be resorted to in the relative arrangement of parts shown and described without departing from the spirit and scope of my invention. Hence I would have it understood that I do not wish to confine myself 105

to the exact construction and arrangement of parts shown and described, but—

Having fully described my invention what I claim as new and desire to secure by Letters-Patent, is:

1. In a car underframe, the combination of a hollow metal cross-sill having a longitudinal slot extending lengthwise its lower member, a bolt passing through said slot and supported solely on the metal of the sill at the sides of the slot, and a hanger secured to the bolt below the sill.
2. In a car underframe, the combination of a box form cross-sill having a slot in its lower member extending lengthwise the sill, the edge of metal at the two sides of the slot being turned over onto itself, a bolt passing from the inside of the sill through the slot, and a hanger secured to said bolt.
3. In a car underframe, the combination of a box form cross-sill having a slot in its lower member extending lengthwise the sill, a washer within the sill and bridging the slot, a bolt passing from the inside of the sill through said washer and slot, and a hanger secured to the bolt.
4. In a car underframe, the combination of a box form cross-sill having a slot in its lower member extending lengthwise the sill, the edges of the metal at both sides of the slot being bent over onto itself, a washer

supported on said bent edges, a bolt passing from the inside of the sill through the washer and slot, and a hanger secured to the bolt.

35

5. In a car underframe, the combination of a box form cross-sill having a slot in its lower member extending lengthwise the sill, the edges of the metal at both sides of the slot being doubled onto itself, a washer bridging the slot and having bent ends interlocking with the bent edges of the sill, a bolt passing from the inside of the sill through the washer and slot, and a hanger secured to said bolt.

40

6. In a car underframe, the combination of a box form cross-sill having a slot in its lower member, extending lengthwise the sill, internal shoulders at opposite sides of the slot, a washer bridging the slot and having bent ends interlocking with said internal shoulders, a bolt passing from the inside of the sill through the washer and slot, and a hanger secured to said bolt.

45

In testimony whereof, I have signed this specification in the presence of two subscribing witnesses.

50

CHARLES H. ANDERSON.
